(57) CLAIM

The ornamental design for a holder for rolls of kitchen paper, as shown and described.

DESCRIPTION

FIG. 1 is a perspective view of a holder for rolls of kitchen paper showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken lines shown in the figures represent portions of the holder for rolls of kitchen paper that form no part of the claimed design.
